HAIRCUTTING APPLIANCE

Léon Abraham Seilaz, Zurich, Switzerland

Application August 22, 1930, Serial No. 477,134
In Switzerland September 5, 1929

1 Claim. (Cl. 30—12)

In order that the hair after cutting lies correctly the hair is cut to a point that is to say care is taken that the hair in a bunch is all cut to different lengths. The so-called cutting to a point or tapering (known by the French term *effiler*) was hitherto effected by means of scissors in that forward and backward movements were carried out therewith on the hair held at the point in one hand whilst separate hair of the bunch were cut. The hair was thus cut to different lengths.

In order to carry out this operation properly many years experience is required. The object of the present invention is to facilitate this work and to provide a simple, inexpensive and readily usable tool so that less skilled persons can effect this pointing of the hair and thus carry out complete hair cutting therewith. A further object of the invention is to provide suitable means which allow a man to cut his hair perfectly without any further aid.

According to the present invention a blade, for example the blade of a razor, a shaving appliance blade and so forth is so arranged on a comb that the cutting edge of the blade partly enters the teeth of this comb. By drawing such a comb through the hair the hair is cut by the blade in such a manner that the hair has different lengths.

Preferably the appliance is so constructed that the cutting edge of the blade is adjustable relatively to the points of the teeth of the comb and is capable of being locked in position. If the cutting edge is locked in a position more or less from the points of the teeth the cutting action is modified. The blade may also be completely removed from the teeth so that the comb may be used as such, not for cutting, but for combing the hair. The device for adjusting the blade is also such that the cutting edge projects beyond the teeth points of the comb. In this position of the blade the cutting edge thereof may be sharpened easily by stropping on a grinding body, leather and so forth.

In the accompanying drawings

Figure 1 is an elevation of a haircutting appliance constructed in accordance with my invention.

Figure 2 is a transverse sectional view of the same.

Figure 3 is an elevation of a modified form of the invention.

Figure 4 is a similar view of another modified form of the same.

Figure 5 is a transverse sectional view of a

modified form of the invention shown in Figure 4.

Figure 6 is a transverse sectional view of another modified form of the invention.

Figure 7 is an elevation of another modified form of the invention.

Figure 8 is a transverse sectional view of the form of the invention shown in Figure 7.

Figure 9 is a longitudinal sectional view of another modified form of the invention.

Figure 10 is an elevation of the same.

Figure 11 is an elevation of the blade used in the form of the invention shown in Figures 9 and 10.

Figures 12, 13, and 14 are detail elevations of modified forms of the blade.

Figure 15 is an elevation of another modified form of my improved haircutting appliance with a portion of the blade removed.

Figure 16 is a transverse sectional view of the same on a somewhat larger scale.

Figure 17 is a transverse sectional view of a construction embodying a modified arrangement of the combs.

Figure 18 is an elevation of another modified form of my improved haircutting appliance.

Figure 19 is a plan of the same.

The appliance according to Figs. 1 and 2 is provided with a double comb 1 of metal, horn, a suitable artificial mass such as celluloid and the like, having a handle 2 in which is rotatably and adjustably mounted a razor blade 4. The double comb 2 is provided with teeth 5. Between the two side portions 7, 8 of the comb is located the blade 4. A stop 9 provided on the handle 2, limits the movement of the blade 4 and includes a set screw 9a which enables the end position of the blade to be varied. The blade 4 is guided by means of a pin 10 in a slot 11 of the handle 2. If the blade 4 is engaged between the teeth of the double comb and the appliance is drawn through the hair to be cut the hair is cut automatically to different lengths. By lifting the blade 4 out of the teeth of the comb 1, 2 the latter is suitable for combing the hair.

The length of the slot 11 and the widths of the blade and comb are such as to enable the blade to be so adjusted that its cutting edge projects beyond points of the teeth and parallel with the common plane of such points, so that it may be readily sharpened as hereinafter stated.

The procedure is preferably first to arrange the hair by means of the comb, then the head is set firmly and the hair dresser then holds a bunch of hair at the ends with the left hand. The short

100

105

110

hair are combed towards the head with the comb and by pressure of a finger the blade 4 is set in the position shown in Fig. 2. The longer hair held by the left hand is then pointed by the blade 4, that is to say cut to unequal length. The bunch of hair, thus cut, then places itself from the inside towards the outside whilst extending to a point uniformly against the head.

Instead of a double comb two adjacently disposed combs 7', 8' (Fig. 17) could be provided. Further the teeth could be inclined relatively to the handle. The blade, instead of being rotatable about the rivet 10, could be arranged to be moved parallel to itself in the comb.

In Figs. 3—14 are illustrated further forms of construction of the appliance wherein flat blades, for example blades of safety razors are used. The front end of a handle 15 (Figs. 3 to 5) formed as a head is provided on both longitudinal sides with teeth, the teeth on both sides being of the same or different fineness. Over the toothed head portion is located a blade shaped steel blade 16, similar to that of a safety razor, and over this is placed a protecting plate 17 which is also provided on both sides with teeth. The teeth of the parts 15 and 17 coincide with one another. The parts 15, 17 form together a comb. For securing the parts 16 and 17 on the handle there are provided screws 18 which pass through slots 19 in the protecting plate 17 and through holes 20 in the blade 16. In Fig. 3 the blade is set in a central position it may, however, as shown in Fig. 4, be moved towards one side so that the cutting edge extends beyond the points of the teeth of the comb 15. The slots 19 in the part 17 enable the part 17 to be moved suitably backwards and forwards over the lower part 15, for the purpose of enabling the shorter hair to be cut without damaging oneself. The parts 15, 17 may be flat as shown in Fig. 5. They may also be arched as shown for example in Fig. 6, so that the blade is curved and is under a certain tension. The protecting plate 17 could also be made wider than the head portion 15 and wider than the blade 16 so that, as shown in Fig. 6 the cutting edge is behind the teeth points of the part 17 and in front of the teeth points of the part 15.

As shown in Figs. 7 and 8 the comb could also be provided on one side with teeth 22 serving for combing purposes but not for cutting whilst on the back of the handle 21 there is again provided a blade 16 which is adjustable and capable of being locked by screws 18. As shown in Figs. 9 and 10 the blade 16 can also be connected to the handle 25 by means of a springy clamping member 26 and a strap 27 provided with headed ends 28 engaging between the limbs of the springy clamping member 26 and thus pressing the protecting plate 29 against the blade 16 and the latter against the head portion 25 of the handle. By forcible pressure on the strap 27 the latter can be removed from the position shown and thus the blade 16 released from the comb 25. The strap 27 may

also be screw threaded at its end for engagement by nuts which press the plate 29 firmly against the comb 25.

The blade 16 itself may have the shape shown in Figs. 11—14. The blade 16 is provided with projections 40, notches 41 and slots 43 of different shapes so that it can be engaged easily with the finger and adjusted in any desired position in the handle.

The blade 16, Fig. 14, is provided with cutting edges inclined relatively to one another, the blade facilitates cutting the hair along the hair limit of the head.

In the form of construction according to Figs. 15 and 16 there is provided on the handle 30 a head with teeth of different fineness on oppositely disposed sides. The blade 32 is provided at its oppositely disposed narrow edges with teeth 33. The blade 32 is secured by a cover plat 34. In the parts 30, 34 are rotatably mounted two peripherally toothed bushes 31. The bushes 31 engage with the teeth 33 of the blade and by turning the bushes the blade 32 can be suitably adjusted. For locking the blade 32 in the desired operative position clamping plates 44 are provided, which when tightened by means of screws 35 clamp the parts 30, 32, 34 together.

The plates 17, 29 and the head portions 15, 21, 25 are each provided with a recess so as to enable the blades 16 to be gripped by hand and moved and adjusted as desired so as to adjust the length of hair cutting.

In the form of construction according to Figs. 18 and 19 two combs 45, 46, having the same teeth spacing, are rotatably connected together by a rivet 48. The separate combs 45, 46 may be turned independently of one another. In the position shown the combs are held by a pin 49 provided on the comb 45. Between the combs 45, 46 the blade 47 is mounted so as to be loosely rotatable. In this construction of the appliance the razor blade can be used with only a single comb or in the manner described in connection with Fig. 1.

What I wish to claim and secure by the U. S. Letters Patent, is:—

A device for combing and cutting hair, comprising a comb element having a double comb, said combs being spaced apart and each provided at one end with a handle having a transverse slot substantially parallel with the teeth of the comb; a blade arranged to enter the space between the combs and provided with a tang arranged between the handles of the combs, a pivot for said blade projecting from the tang thereof and movable in the slots of the handles and means whereby the blade may be adjusted to dispose its cutting edge at any desired distance within the points of the comb teeth according to the desired length of the hair or to a position beyond the said points and parallel with the common plane thereof, to enable said edge to be sharpened.

LÉON ABRAHAM SEILAZ.
